UNITED STATES PATENT OFFICE.

DAVID DIMENTBERG, OF CHICAGO, ILLINOIS.

ELECTRIC SCONCE.

Application filed February 17, 1926. Serial No. 88,881.

This invention relates to electric sconces usually fitted to mirrors, framed pictures and the like for purposes of illumination and ornamentation, and its object is to provide an appliance of this kind which is a separate unit and is attachable to the frame of the mirror, picture or the like at will.

A further object of the invention is to provide an appliance of this kind which may be packed and shipped separately from the frame to which applied, enabling the latter to be compactly packed, especially when shipped in quantities.

A still further object of the invention is to eliminate the need of boring holes in the frame and the danger of cracking or otherwise marring the surface finish thereof.

Another object of the invention is to provide a self-contained unit for electric illumination which is properly wired at the outset and relieves the user of labor in that connection.

A final but nevertheless important object of the invention is to construct the novel appliance of few and simple parts, whereby it may be marketed at small expense.

With the above objects in view, and any others which may suggest themselves in the specification and claims to follow, a better understanding of the invention may be gained by reference to the accompanying drawing, in which:—

Figure 1 is an elevation of a corner of a mirror, showing the novel sconce mounted;

Fig. 2 is an enlarged section on line 2—2 of Figure 1, a portion of the mirror being cut away to reveal the shank of the sconce;

Fig. 3 is a perspective view of as much of the sconce and the mirror as enter into the assembly of the appliance; and

Fig. 4 is a perspective view of the sconce shank showing a locking ring.

Referring specifically to the drawing, 10 denotes the frame of a mirror, picture or the like, to which a sconce 11 of any approved design is intended to be applied. Sconces of the prevalent type are adapted to receive an electric lamp socket, the lamp cord passing down through the base 12 of the sconce and issuing from a tube 13 which projects from the back of such base.

The usual practice has been to drill the frame 10 to receive the tube 13 as the sconce is applied, and to provide means on the back of the frame to secure the tube and protect

the lamp cord. Obviously, the drilling of the hole or the tightening of the sconce would frequently cause the plaster or other surface covering to crack, break off or become badly marred; also, the disposal of the lamp cord often caused short-circuiting of the wires from frictional contact of the cord with the end of the tube.

In the present embodiment, the sconce and its fittings are applied to the frame without altering the same in any manner or subjecting the surface coating thereof to any strain or friction. The sconce is applied with its shank positioned next outside the frame whereby to clear the coated portion thereof.

In carrying out the invention, a sleeve 14 is slid upon the tube 13, the sleeve carrying a set screw 15 to bear on the tube and thus fasten the sleeve to the latter. The sleeve is intended not to turn on the tube, and is therefore cut with opposed notches 16 in its forward end to seat upon ridge-shaped lugs 17 projecting from the sconce base adjacent to the tube.

The sleeve 14 is open on that side which is nearest the frame, and is formed with a horizontal wing 18. The wing is adapted to receive from below a bracket 19 of inverted L-shape. The horizontal section of the bracket and the wing 18 are apertured for pivotal connection by a bolt and nut 20. The other section 19^a of the bracket is slightly tapered and drilled with an aperture 21.

As regards the frame 10, a plate 22 is secured to the back thereof by screws 23 and has an outwardly directed wing 24 whose main portion is resilient and slightly spaced from the frame while its extremity is formed with a short bend 25 toward the frame. It will be seen that the plate 22 forms a receptacle for the bracket to support the sconce to the frame by lowering and snugly fitting the bracket section 19^a into the pocket formed by the wing 24 and the back of the frame. While the sconce is suitably supported in the above manner under ordinary conditions, an additional fastening may be supplied by driving a screw through the aperture 21 of the bracket into the back of the frame.

The lamp cord 26 leading from the sconce 10 terminates, as in the case of lamps, irons and like electrical appliances, in a plug—not shown—which is fitted into a wall receptacle or other current dispensing device. In the present case the cord also carries

at any intermediate point—a tubular nipple 27 of hard rubber, whose rear or outer end is internally rounded—as indicated at 27^a—to let the cord emerge in any direction gradually and without friction. This nipple is a standard fitting in the small lamp class and is usually made with a reduced and threaded shank 27^b.

The side opening in the sleeve 14 enables

- 10 the cord to be easily inserted therein as the sleeve is about to be slid on the sconce tube 13; and once the sleeve is fast on the tube, the nipple can be inserted to close the open end of the sleeve. The sleeve need not be tapped to receive the nipple, since its internal diameter and inherent tension will contribute toward a snug fit. However, to assure the permanency of the connection, the sleeve may be cut with a transverse slit 28—
- 15 on which a section is cut in Figure 4—to receive an incomplete ring or washer 29 of thin steel. This ring is formed with longitudinal undulations and is placed under tension when pressed into that thread of the nipple shank 27^b which is located opposite it. The ring thus acts as a lock to prevent the nipple from receding from the sleeve; yet it may be easily removed with a pin or wire in case the nipple is to be
- 20 detached.

A device is thus had which fulfills the objects contemplated. In case it is desirable to attach the sconce to the frame before delivering or shipping, the pivotal connection at 20 is useful for swinging the sconce out to extend beyond the frame and therefore facilitate flat packing and handling without danger of injury to the surface of the frame. Also, the said pivotal connection enables

- 25 the sconce to be swung sidewise and set at an angle, if desired, the adjustment being fixed by tightening the connection at 20.

As to the sleeve 14, loosening the set screw 15 permits the sconce to be rotated in one or the other direction—with the tube 13 as an axis—to place it at an angle or in inverted position. Further, the lateral slot in the sleeve 14 makes it very easy to remove the lamp cord 26 after the sconce tube 13 has been slid out of the sleeve in a forward direction. Electrical connections therefore need not be disturbed, the only labor required to remove the sconce and the cord being to loosen the screw 15, slide the tube 13

out of the sleeve, pry out the washer 29 and 55 pull out the nipple 27.

While the drawing shows the preferred embodiment of the invention, it should be understood that many changes or refinements may be made therein; and these 60 changes and refinements I wish to include as coming within the scope and spirit of the appended claims.

I claim:—

1. A sconce fitting for mirror frames and 65 the like comprising a shank alongside the edge of the frame, an electric current supply conductor passing through said shank, a part-open sleeve receiving the said conductor laterally and fitted to the shank, a 70 bracket formed from the sleeve, and receptacle attached to the back of the frame to receive said bracket.

2. A sconce fitting for mirror frames and the like comprising a shank alongside the 75 edge of the frame, an electric current supply conductor passing through said shank, a part-open sleeve receiving the said conductor laterally and fitted to the shank, a 80 bracket formed from the sleeve, a pivot joint incorporated in the bracket, a receptacle attached to the back of the frame to receive said bracket.

3. A sconce fitting for mirror frames and the like comprising a shank alongside the 85 edge of the frame, an electric current supply conductor passing through said shank, a part-open sleeve receiving the said conductor laterally and fitted to the shank, a non-frictional outlet for said conductor fitted to said 90 sleeve, a bracket formed from the sleeve, and a receptacle attached to the back of the frame to receive said bracket.

4. A sconce fitting for mirror frames and the like comprising a shank alongside the 95 edge of the frame, and electric current supply conductor passing through said shank, a part-open sleeve receiving the said conductor laterally and fitted to said shank, a non-frictional outlet for said conductor fitted to said 100 sleeve, a locking element for the said outlet carried by said sleeve, a bracket formed from the sleeve, and a receptacle attached to the back of the frame to receive said bracket.

In testimony whereof I affix my signature.

DAVID DIMENTBERG.
